UNITED STATES PATENT OFFICE.

VERNON ROYLE, OF PATERSON, NEW JERSEY.

CIRCULAR LOOM.

1,153,576.

Specification of Letters Patent. Patented Sept. 14, 1915.

Application filed August 22, 1914. Serial No. 858,108.

To all whom it may concern:

Be it known that I, VERNON ROYLE, a citizen of the United States, and resident of Paterson, in the county of Passaic and State 5 of New Jersey, have invented a new and useful Improvement in Circular Looms, of which the following is a specification.

My invention relates to circular looms and more particularly to the weaving pin and parts intimately associated therewith, with the object in view of providing improved means for adjusting the weaving pin either laterally or vertically within its support, and further, for adjusting the weaving 15 point or weaving pin carrier in a fixed support.

My invention further contemplates a weaving pin and weaving pin carrier with their several adjustments complete in itself, 20 the whole constituting a self-contained unit which can be used not only upon a loom built specifically for the purpose, but upon circular looms of different general constructions.

25 In the accompanying drawings, Figure 1 is a top plan view of the weaving pin and parts immediately associated therewith, partly broken away to show the position of one of the screws for centering the weaving pin carrier and hence the weaving pin carried thereby. Fig. 2 is a view of the same in side elevation. Fig. 3 is a vertical section in the plane of the line A—A of Fig. 1. Fig. 4 is a partial vertical section in the plane of the line B—B of Fig. 1, and Fig. 35 5 is a partial horizontal section in the plane of the line C—C of Fig. 3.

The base or main supporting piece of the pin structure is denoted by 1, and is here 40 shown of circular form and is conveniently provided with bolt holes 2 for securing it fixedly to a circular loom in substantial axial alignment with the center column or support of the loom, such, for example, as 45 the loom shown, described and claimed in my pending application Serial No. 665991, filed December 15, 1911. The fixed support 1 is a ring and has on its interior face a screw-thread 3, which registers with an external screw-thread 4 on an annular nut 5, which carries the weaving pin carrier 6, in which the weaving pin 7 is supported.

50 The weaving pin carrier 6 is provided with an annular lip or ledge 8 which rests on an annular shoulder 9, formed on the interior face of the nut 5, so that as the nut 5

is moved up and down by turning it within the screw-threaded base 1, the weaving pin carrier 6 and the pin 7 carried thereby, will be raised and lowered. To lock the nut 5 and the parts carried thereby in the desired vertical adjustments, plungers 10 and 11 on diametrically opposite sides of the base 1, are seated respectively in bores 12 and 13, tapped horizontally through the base 1, the outer end of each plunger 10, 11, being formed conical, as shown at 14, and these conical outer ends of the plungers are engaged by the conical ends 15 of adjusting screws 16, 17, tapped from the upper face of the base 1, through into the bores 12 and 13. Those portions of the base 1 which receive the screws 16, 17, are conveniently thickened to form suitable bearings for the screws.

55 It will be observed that the structure is such that when the screws 16, 17, are screwed downwardly, they will force the plungers 10, 11, laterally into engagement with the screw-thread 4 on the nut 5, and hence lock the nut against a rotary movement. When 60 it is desired to rotate the nut, these screws 16, 17, are unscrewed, permitting the plungers to recede from the screw-thread 4, or at least to offer no pressure sufficient to prevent the nut 5 from turning. The outer ends 65 of the bores 12 and 13 are conveniently closed by plugs 18.

70 The weaving pin carrier which carries the weaving pin 7, is allowed sufficient lateral play within the nut 5, to permit of centering the weaving pin carrier with reference to the center of weaving, and this centering of the weaving pin carrier 6, is accomplished by means of four screws 19, 20, 21, 22, conveniently located a quadrant's distance apart 75 and having a screw-threaded engagement with holes formed in the body of the nut 5.

75 The weaving pin carrier 6 is hollow and the lower portion thereof is provided with an interior screw-thread 23 which interengages an external toothed screw-thread 24 formed on the lower portion of the weaving pin 7. The threads 23, 24, are preferably 80 flat faced and the teeth on the thread 24 of the weaving pin 7 form a rack which is engaged by a pinion 25, seated in a vertical socket 26, the lower end of the pinion being journaled in the bottom wall of the socket 26 and the upper end of said pinion being journaled in a journal box 27 fitted in the 85 upper end of the socket 26. The upper journal of the pinion 25 is provided with a kerf 90

28, so that the pinion 25 may be turned by means of a screw-driver or other suitable instrument. The teeth on the pinion 25 are preferably made sufficiently long to engage 5 the rack on the screw 24, at each convolution of the thread, so that when the pinion 25 is turned, it will act upon the thread 24 and hence upon the weaving pin 7, at each of the several convolutions of the thread, and 10 the teeth on the thread 24 will slide up or down against the teeth on the pinion 25, as the weaving pin 7 is raised and lowered by its radial movement in engagement with the internal thread 23 on the weaving pin 15 carrier.

The weaving pin 7 is hollow or tubular and its upper portion is fitted so as to slide with a close sliding fit in the upper end of the weaving pin carrier.

20 To lock the weaving pin against any tendency to rotate within the weaving pin carrier 6, after it has been adjusted to the desired elevation within the carrier, a screw 30, is set in the wall of the weaving pin carrier 6, in proximity to the upper journal of the pinion 25, so that the head of the screw will lap over a portion of the journal box 27, as clearly shown in Fig. 4, and when the screw 30 is screwed inwardly, the journal box 30 27 will press the pinion 25 endwise against its lower bearing, producing sufficient friction to hold it against unintentional rotary movement. When it is desired to rotate the pinion 25, the screw 30 is loosened.

35 For convenience in turning the nut 5 in the base 1, the rim of the nut may be provided with holes 29, at suitable intervals in which the end of a small operating lever may be inserted.

40 The foregoing structure provides for elevating and lowering the weaving pin carrier 6 and the weaving pin 7 carried thereby, by turning the nut 5 in the base 1 and the nut 5 may be locked with the parts carried thereby in its adjusted position by the screws 16, 45 17. Furthermore, the weaving pin carrier and weaving pin carried thereby, may be centered with respect to the axis of weaving by moving it horizontally within the nut 5 50 and locking it in position by means of the screws 19, 20, 21, 22. The weaving pin 7 may be further adjusted vertically relative to the weaving pin carrier, leaving more or less of the pin 7 exposed above the carrier 55 6, to increase or decrease the friction on the woven tube by unlocking the pinion 25 and turning it in the one direction or the other and thereby screwing the pin 7 up or down within the carrier 6. This structure provides means for accurately adjusting the 60 weaving pin by means in close association with the pin, and the pin and the parts immediately connected therewith are so arranged that they form a weaving pin unit 65 capable of application to circular looms

already manufactured as well as to looms manufactured particularly to receive it.

What I claim is:

1. A weaving pin provided with an external screw thread, a weaving pin carrier 70 embracing the weaving pin and provided with an internal screw-thread in position to engage the screw-thread on the weaving pin for projecting the weaving pin to a greater or lesser extent through the carrier, and 75 means for locking the pin in the desired adjustment.

2. A tubular weaving pin provided with an external screw-thread, a weaving pin carrier 80 adapted to embrace the weaving pin 80 and provided with an internal screw-thread in position to engage the external screw-thread on the pin for projecting the weaving pin to a greater or lesser extent through the carrier, and means for locking the pin 85 in the desired adjustment.

3. A weaving pin, a weaving pin carrier, an element in which the weaving pin carrier is supported and means for adjusting the weaving pin carrier laterally in said element in any desired direction for centering the weaving pin.

4. A weaving pin and its carrier, the carrier being provided with a screw-thread and the pin with a combined gear and 95 thread constructed to register with the thread in the carrier, and a pinion for rotating the pin within the carrier to adjust the pin relative to the carrier.

5. A weaving pin, a weaving pin carrier, 100 the weaving pin and carrier having interengaged screw-threads, the thread on the pin being provided with gear or rack teeth, a pinion in position to engage said gear or rack teeth and a stop in position to increase friction on the pinion to lock it and hence the weaving pin against unintentional rotary movement in the weaving pin carrier.

6. A weaving pin, a weaving pin carrier, 110 a base, and a nut having a screw-threaded engagement with the base and supporting the weaving pin carrier for adjusting the latter and hence the weaving pin, horizontally.

7. A weaving pin, a weaving pin carrier, a base, and a nut having a screw-threaded engagement with the base for adjusting the weaving pin carrier and hence the weaving pin longitudinally, and means in connection 120 with the base for locking the nut against unintentional rotative adjustment.

8. A weaving pin, a weaving pin carrier, means for adjusting the pin longitudinally within the weaving pin carrier, a nut for supporting the weaving pin carrier and a 125 base with which the nut engages for adjusting the weaving pin carrier and the weaving pin carried thereby.

9. A weaving pin, a weaving pin carrier, 130 a nut for supporting the weaving pin, a base

with which the nut has a screw-threaded engagement, and interengaging conical-ended plungers and screws for locking the nut against unintentional rotative movement.

5 10. A weaving pin, a weaving pin carrier embracing the weaving pin, the pin having a rotative longitudinal adjustment within the carrier, means carried by the pin carrier for rotating the pin, said means being operative from the side of the carrier toward

the outer end of the pin, and means for locking the pin against unintentional rotation.

In testimony, that I claim the foregoing as my invention, I have signed my name in presence of two witnesses, this twenty-ninth 15 day of July, 1914.

VERNON ROYLE.
